RESERVOIR SEAL

Hans Reinhard Fehling, Zug, Switzerland, and Edward Henry Harvey, London, England, assignors to I.R.C. Limited, London, England, a company of Great Britain
Filed July 19, 1961, Ser. No. 125,217
Claims priority, application Great Britain July 30, 1960
5 Claims. (Cl. 120—42.4)

This invention relates to seals for liquid reservoirs in dispensing instruments or the like and, more particularly, to a new and improved reservoir seal which is effective in all orientations of the reservoir.

This application is a continuation-in-part of our copending application for "Seal for Reservoirs of Writing and Other Dispensing Instruments," Serial No. 5,872, filed February 1, 1960. In the copending application there is described a seal for a liquid reservoir having a bore open at one end to the exterior of the reservoir comprising a solid follower piston slidable in the bore having one end immersed in the reservoir liquid and forming a clearance space of capillary dimensions between itself and the walls of the bore. To balance the capillary and other forces tending to draw the follower into the reservoir liquid, the copending application discloses various arrangements for urging the follower out of the reservoir liquid and, in one embodiment, a compression spring is provided inside the reservoir for this purpose.

In reservoir seals of this type, the spring exerts on the piston, in all orientations of the reservoir, a force tending to urge the piston out of the reservoir liquid. As a result of this force the pressure in the reservoir is decreased by an amount corresponding to the capillary pressure set up by this force, thus tending to cancel the positive head of liquid in the reservoir. This effect is most pronounced when the reservoir is nearly empty, in which condition the spring is almost fully compressed and there then arises a limitation as to the extent to which the reservoir can be emptied under gravity.

In a liquid reservoir for a writing instrument such as a ball-point pen, it is highly desirable to convey the writing liquid to the writing extremity under a positive head, in order that the instrument shall function satisfactorily. Consequently, in a reservoir of the type referred to, it becomes desirable to eliminate or at least reduce the effect of the spring upon the piston in the normal writing attitude of the reservoir.

Accordingly, it is an object of the present invention to provide a new and improved reservoir seal which overcomes the above-mentioned disadvantage of known seal arrangements.

Another object of the present invention is to provide a liquid reservoir seal which is uniformly effective in all orientations of the reservoir.

These and other objects of the invention are accomplished by providing, in a reservoir having a bore and a follower piston slidable in the bore along with an arrangement for urging the piston out of a liquid in the bore in all orientations of the reservoir, means for modifying the force applied by the urging arrangement when the reservoir is in a vertical orientation. In one embodiment of the invention, in which the urging means is a compression spring within the reservoir, the means for modifying the force comprises a weight interposed between the spring and the piston.

Further objects and advantages of the invention will be apparent from a reading of the following description in conjunction with the accompanying drawings, in which:

FIGURE 1 is a view in longitudinal section through a ball point writing instrument having a reservoir seal ar-

2

ranged according to the invention and positioned with the writing point downward;

FIGURE 2 is a view in longitudinal section through the instrument of FIGURE 1 positioned with the writing point upward; and

FIGURE 3 is a fragmentary view in section through the relevant part of the reservoir of FIGURES 1 and 2 showing the relative attitudes of the weight and follower when the reservoir is horizontal.

10 While the invention is applicable to reservoirs of writing instruments such as fountain pens, stylographic pens, and ballpens and ball-point pens, it is also applicable to dispensing instruments or applicators (primarily those having a ball-tip or ball-valve discharge end) such as 15 may be used for dispensing or applying deodorants, scent and other cosmetics. It is especially applicable to the reservoirs of ball-point writing instruments, for the difficulties which the invention seeks to reduce have chiefly arisen in connection with ball-point writing instruments.

20 In the representative embodiment of the invention shown in FIGURES 1, 2 and 3 the reservoir of a ball-point writing instrument is numbered 10, the column of ink or other reservoir liquid 11, and the piston follower 12. The follower 12 is an easy sliding fit in the bore and 25 forms a capillary annular clearance with the wall of the bore. This clearance is occupied by the liquid 11 which presents a meniscus at the rear end of the annular clearance and thus forms a seal. If desired, a different sealing liquid may be used. It is important that the follower 12 is slightly buoyant, i.e., its overall specific 30 gravity or bulk density is slightly less than that of the reservoir liquid 11 in order that it does not sink. The interior of the reservoir constitutes the bore aforesaid; it is desirably of circular cross section and smooth.

35 In a reservoir seal of the kind thus far described, one end or face of the follower 12 is immersed in the reservoir liquid 11 whilst the other end or face (usually subject to atmospheric pressure) emerges from the liquid with the result that at the latter end a small meniscus is formed 40 at the surface of the thin annulus of liquid filling the clearance between the follower periphery and the reservoir wall.

If this meniscus is concave, the resulting capillary forces 45 produce a depression (below atmospheric pressure) in this annulus of liquid. In consequence there is a pressure difference between the two faces or ends of the follower 12 which, even if the latter has the same bulk density (apparent specific gravity) as the liquid 11 tends to force the follower into the liquid.

50 If this force is not balanced by an opposing force, the follower 12 will move into the liquid 11 and extrude the latter through the above-mentioned annular clearance. This condition normally exists when the writing instrument lies on its side. Movement of the follower into the

55 liquid will continue until the concave meniscus changes its shape in such a way that the resulting capillary forces no longer reduce the hydrostatic pressure in the reservoir, i.e., when in effect the pressure difference between the two ends of the follower has vanished. The capillary pressure can only decrease if the radius of the meniscus increases, i.e., if a strong, stable meniscus changes into a weak and usually unstable meniscus, whether slightly convex or slightly concave. When this happens there is 60 danger of liquid seepage towards the rear end of the reservoir, especially if there already exists a film of liquid on the reservoir wall behind the follower (as may happen due to the liquid level being lowered by the dispensing of liquid).

65 There is another and additional reason why there is danger of seepage. When the reservoir is lying on its side the annulus of liquid between the follower periph-

ery and the reservoir wall, at the lower part of the lower periphery, is subjected to a positive hydrostatic head the magnitude of which is proportional to the diameter (or equivalent dimension) of the reservoir. Hence it is at this lower part of the follower periphery that liquid seepage takes place, unless the hydrostatic head at each point of the annular surface of the liquid is balanced by the local capillary pressure (depending on the local radius of curvature of the liquid surface).

In this specification the expression "strong meniscus" is used to indicate a meniscus which is very stable (and not one where the surface tension force is particularly high, for surface tension is constant and independent of curvature): the most important feature producing stability is a small radius of curvature, because such a meniscus will not practically change its shape in various positions of the instrument.

In order to reduce the above-mentioned seepage of liquid, a compression spring 20 is inserted in the bore of the reservoir to urge the piston 12 out of the liquid 11 with a force insufficient to expel the follower from the liquid, as described in the above-mentioned copending application. Inasmuch as the follower 12 is buoyant, however, the total force urging it out of the liquid 11 would be greater in the upright position shown in FIGURE 1 than in the inverted position shown in FIGURE 2 in the absence of any means for modifying the force and this obviously imposes a limitation on the range of forces which can be applied to the follower by the spring 20 without expelling it from the liquid.

In accordance with the present invention, therefore, there is inserted between the compression spring 20 and the follower 12 a ball 21 made of heavy material, e.g. metal. The weight of this ball 21 is preferably such as fully to compress the spring as shown in FIGURE 1 when the reservoir is vertical with the writing point downward. When the reservoir 10 is horizontal as shown in FIGURE 3, the ball 21 has no effect on the follower 12 since its weight is carried by the lower portion of the reservoir wall. When the reservoir is inverted, i.e., with the follower downwards as shown in FIGURE 2, it is important that the maximum outward thrust of spring 20 and ball 21 on the follower 12 shall not be sufficient to eject the follower from the reservoir liquid, i.e., the maximum outward thrust on the follower must not exceed the value corresponding to the maximum permissible pressure differential across the liquid meniscus as set out in the copending patent application. The maximum outward thrust occurs when the reservoir is almost empty and in the inverted attitude, that is to say when the weight of the ball 21 is added to the thrust of the spring 20 in its almost fully compressed condition. It will be understood that the forces acting on the follower must be insufficient to overcome the capillary forces in the narrow gap between the ball and its housing. When changing the reservoir from the writing position in which the follower is uppermost, to the horizontal position, the ball 21 rolls along the reservoir under the influence of the spring 20. It is thought that this rolling action is advantageous in that it avoids the sticking which might occur were the weight merely slidable along the reservoir.

In a typical reservoir for a writing instrument made according to the invention, the important dimensions were as follows:

Reservoir bore diameter.....	mm.....	5.0
Follower diameter.....	mm.....	4.9
Mean radial clearance.....	mm.....	0.05
Length of uncompressed spring.....	cm.....	7.5
Length of spring when reservoir full.....	cm.....	5.5
Number of turns.....		100
Mean diameter of turns.....	mm.....	4.75
Wire diameter of brass spring.....	mm.....	0.11
Spring rate.....	gm./cm.....	0.08
Specific gravity of ink.....		1.1

Diameter of heavy ball.....	mm.....	4.8
Specific gravity of heavy ball.....	gm.....	8.95
Weight of heavy ball in air.....	gm.....	0.52
Weight of heavy ball in ink.....	gm.....	0.46
Buoyant force on follower when immersed in ink.....	gm.....	0.06
Maximum allowable outward thrust on follower (corresponds to (Po-Pi) _{max} condition).....	gm.....	1.1
Minimum allowable outward thrust on follower (corresponds to (Po-Pi) _{min} condition).....	gm.....	0.05

As is fully described in our copending application identified above, the (Po-Pi)_{max} and (Po-Pi)_{min} conditions are the conditions in which the pressure differential across the liquid meniscus surrounding the follower is at the maximum and the minimum permissible values, respectively.

In operation, when the writing instrument is in the upright position shown in FIGURE 1, the follower 12 is urged out of the reservoir only by the buoyant force acting on it, the spring 20 being compressed by the ball 21. In the inverted position shown in FIGURE 2, the weight of the ball 21 and the force of the spring are combined to oppose the buoyant force acting on the follower 12 and urge the follower out of the reservoir with sufficient force to balance the capillary force drawing it into the liquid. With the reservoir horizontal as shown in FIGURE 3, the buoyant force and the weight of the ball act only in the transverse direction and the force of the spring 20 is the only force urging the follower out of the liquid.

Although the invention has been described herein with reference to a specific embodiment, many modifications and variations therein will readily occur to those skilled in the art. Accordingly, all such modifications and variations are included in the intended scope of the invention as defined by the following claims.

We claim:

1. A liquid reservoir including a seal comprising a conduit having a forward end and a rear end and having a bore of greater-than-capillary cross-sectional area which is subject to atmospheric pressure, piston means slidable within the conduit and having a peripheral shape similar to but slightly smaller than that of the inside surface of the conduit so as to provide a space of capillary dimensions between the adjacent surfaces of the piston means and the conduit, urging means effective when the reservoir conduit is in a first position between horizontal orientation and an orientation wherein one of said rear end and said forward end is lower than the other thereof for applying a component of force to the piston means directed in the longitudinal direction of the conduit in a manner tending to thrust the piston means out of a liquid in the conduit which is sufficient to balance any capillary forces tending to draw the piston means into a liquid in the conduit, thereby preventing seepage of liquid through the space between the piston means and the conduit, and means for modifying the component of force applied by the urging means to the piston means when the reservoir conduit is in a second position wherein said other of said forward and rear ends is lower than said one thereof, said modifying means being ineffective to vary the component of force applied by said urging means to said piston means in said first position of said conduit.

2. A liquid reservoir according to claim 1 wherein the means for modifying the component of force applied by the urging means is responsive to gravity.

3. A liquid reservoir according to claim 1 wherein the piston means has a bulk weight which differs in one direction from that of a liquid to be contained in the reservoir conduit and the means for modifying the urging means component of force comprises a member movable within the reservoir conduit having a bulk weight which differs in the other direction from that of the liquid to be contained in the reservoir.

4. A liquid reservoir according to claim 1 wherein the

urging means comprises a compression spring located within the reservoir conduit.

5. A liquid reservoir according to claim 4 wherein the means for modifying the urging means component of force comprises a member movable within the reservoir conduit having a bulk weight greater than that of a liquid to be contained in the reservoir interposed between the compression spring and the piston means.
